UNITED STATES PATENT OFFICE.

JOHN H. GREEN, OF AURORA, ILLINOIS, ASSIGNOR OF FORTY-NINE ONE-HUNDREDTHS TO DANIEL J. SMITH, OF SAME PLACE.

ADJUSTABLE HOOP.

SPECIFICATION forming part of Letters Patent No. 664,082, dated December 18, 1900.

Application filed March 15, 1900. Serial No. 8,755. (No model.)

To all whom it may concern:

Be it known that I, JOHN H. GREEN, of Aurora, Illinois, have invented certain new and useful Improvements in Adjustable Hoops, 5 of which the following is a specification.

This invention relates to improvements in adjustable hoops for receptacles—such as pails, boxes, barrels, &c.—and refers more specifically to a construction in which the several hoops constituting a set are united at their respective ends to clamping bars or clips, whereby they may be all simultaneously tightened or loosened.

Among the objects of the invention are to provide a construction wherein all of the several hoops may be tightened without changing their positions upon the vessel and also without the necessity of adjusting a separate device for each hoop; to provide a construction in which the hoops of the entire set may be made of a single continuous wire or cable; to so construct and arrange the parts that the entire set of hoops may be applied to the vessel or removed therefrom together with the greatest expedition; to provide such a construction that a length of any ordinary wire of suitable size may be used to form the hoops, thus enabling the user of the vessel to repair the same with the minimum delay, trouble, and expense, and in general to provide a simple and improved construction of the character referred to.

To the above ends the invention consists in the matters hereinafter set forth, and more particularly pointed out in the appended claims, and will be readily understood from the following description, reference being had to the accompanying drawings, in which—

Figure 1 is a view of a pail or tub shown in side elevation equipped with a preferred embodiment of my invention. Fig. 2 is a fragmentary end view of that part of the vessel against which the tensioning-clamps rest, the latter being shown in end plan.

Referring to said drawings, 1 designates as a whole a pail or other vessel composed of a plurality of staves, as 2, assembled as usual, and 3 4 designate a pair of clamping-bars arranged to extend longitudinally of the vessel approximately parallel with each other and at a slight distance apart, so as to per-

mit their approach to tighten the hoops, as will hereinafter appear. Each of said clamping-bars consists in the preferred embodiment shown in the drawings of a bar or plate of 55 sufficient length to extend across the entire set of hoops and consisting of a base portion 5, formed to rest flatly against the side of the vessel, and an outstanding portion or flange 6 of sufficient width or height to receive tensioning-screws 7, which are inserted therethrough at intervals apart throughout the length of the bars.

In the particular embodiment shown herein the clamping-bar 3 is provided with threaded 65 apertures to receive the threaded ends of the tensioning-screws, while the opposite bar 4 is provided with apertures through which the screws pass loosely, so that the bars may be drawn together by simply turning the screws 70 by means of a screw-driver; but it will of course be obvious that any suitable clamping screw or bolt may be employed instead of the particular form shown. Each of the base-plates 5 is provided at its edge remote from 75 the flange 6 with an upturned portion or hook-shaped flange 8, adapted to receive and hold a wire or cable 9, which forms the several hoops of the vessel, said flange 8 being notched or apertured at suitable intervals apart, as 80 indicated at 10, to permit those portions of the wire which extend between the connected pairs of hoops to be passed into looped engagement with the flanges, as indicated clearly in Fig. 1. In the preferred construction illus- 85 trated in said figures one end of the wire 9, forming the said hoops, is engaged with the flange 6 of one of the clamping-bars adjacent to one end thereof by extending it through a suitable aperture 11 and bending its extreme 90 end back upon itself to form a head, as best indicated at 12 in Fig. 2. The wire thus engaged with this bar is extended through the notch 10, arranged in circumferential alinement with the aperture 11, carried around the 95 vessel and engaged with the hook-flange of the opposite bar, entering said flange at the uppermost notch or that in circumferential alinement with the starting-point of the wire and passing out at the next lower notch, thence 100 around the vessel and into similar engagement with the opposite bar, and so on through-

out the length of the vessel. The extreme end of the hoop-wire is passed through an aperture 13, formed in the flange 6 of the clamping-bar similar to the aperture 11; but this 5 end of the wire is screw-threaded to receive the nut 14, whereby the loop may be tensioned to some extent. After the hoop-wire has thus been engaged with the clamping-bars so as to form the several hoops the tensioning-screws 10 7 are turned up to draw the clamping-bars together, and thus bring all of the hoop-sections under the required degree of tension.

It will be obvious from the foregoing description that the clamping-bars may be suitably notched to receive any required number 15 of hoop-sections, or, in other words, that the several hoops may be spaced apart at whatever distance is deemed desirable by simply varying the position of the several notches in 20 the hooked flanges. It will be further obvious that the degree of tension brought upon the hoops may be varied at will and that the hoops may be tightened from time to time, as required.

25 It will be obvious from the foregoing description that I attain the several objects of my invention in a simple, reliable, and inexpensive manner.

While I have described my invention as 30 embodied in a device for hooping or banding a staved receptacle, yet it will be obvious that with but little or no modification the device is adapted for use in banding boxes, pails, or other packages, and I do not therefore wish 35 to be understood as in any sense limiting the invention to the particular application described herein. It will be further obvious that the details of construction may be modified to some extent without departing from 40 the spirit of the invention; and I do not therefore wish to be limited to the precise details shown, except as hereinafter specifically claimed.

I claim as my invention—

45 1. As a new article of manufacture, a pair of clamping-bars each comprising a flat base portion, and a flange portion arranged to extend at an abrupt angle from the base portion, a plurality of tensioning devices con-

necting said flange portions, and means for 50 securing thereto a continuous length of hoop-iron laced back and forth to form a plurality of hoops, substantially as described.

2. In combination with a receptacle, a set 55 of hoops and tensioning devices therefor comprising a pair of clamping-bars, each consisting of a base portion adapted to rest in bearing with the exterior of the receptacle, a flange portion arranged to extend outwardly from the base portion, and a hoop-engaging 60 portion, a plurality of tensioning devices operatively connecting said clamping-bars whereby they may be drawn toward each other, and a plurality of hoop-sections formed from a single continuous length of wire or cable 65 having its ends engaged with one of said bars at points remote from each other, and having its intermediate portions extended around the receptacle alternately in opposite directions and engaged with clamping-bars lace 70 fashion, substantially as described.

3. In combination with a receptacle, a set 75 of hoops and tensioning devices therefor comprising a pair of clamping-bars, each consisting of a base portion adapted to rest in bearing with the exterior of the receptacle, a flange portion arranged to extend outwardly from the base portion, and a hoop-engaging 80 portion consisting of a hook-shaped flange formed upon that edge of the base portion remote from the flange thereof and provided with a plurality of notches or interruptions, a plurality of tensioning devices operatively connecting said clamping-bars whereby they 85 may be drawn toward each other, and a plurality of hoop-sections formed from a single continuous length of wire or cable, having its ends engaged with one of said bars at points remote from each other, and having its intermediate portions extended around the receptacle 90 alternately in opposite directions, and engaged with the clamping-bars lace fashion, substantially as described.

JOHN H. GREEN.
